(57) **CLAIM**

I claim the ornamental design for a tabletop remote load control device, as shown and described.

DESCRIPTION

FIG. 1 is a perspective view of a tabletop remote load control device according to a first embodiment of my new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a tabletop remote load control device according to a second embodiment of my new design.

FIG. 8 is a front view thereof.

FIG. 9 is a bottom view thereof, the left side, right side, and top views, respectively, of the second embodiment being identical to the left side, right side, and top views of the first embodiment.

FIG. 10 is a perspective view of a tabletop remote load control device showing an alternate environment of the first embodiment.

FIG. 11 is a front view thereof.

FIG. 12 is a bottom view thereof, all other views being identical to the first embodiment.

FIG. 13 is a perspective view of a tabletop remote load control device showing an alternate environment of the second embodiment.

FIG. 14 is a front view thereof; and,

FIG. 15 is a bottom view thereof, all other views being identical to the second embodiment.

The rear views form no part of the design and are omitted. The broken lines showing portions of the tabletop remote load control device are for the purpose of illustrating environmental structure and form no part of the claimed design.
